UNITED STATES PATENT OFFICE.

NICHOLAS OROS, OF CHICAGO, ILLINOIS.

IRONING DEVICE.

1,075,788.

Specification of Letters Patent.

Patented Oct. 14, 1913.

Application filed May 10, 1913. Serial No. 766,692.

To all whom it may concern:

Be it known that I, NICHOLAS OROS, a subject of the Emperor of Austria-Hungary, and a resident of the city of Chicago, county 5 of Cook, and State of Illinois, have invented certain new and useful Improvements in Ironing Devices, of which the following is a specification.

My invention relates to ironing devices 10 and more particularly to means for applying pressure to a sad iron.

The object of this improvement is to provide a device of the character mentioned which will be simple in construction and 15 efficient in operation.

The invention consists in the combinations and arrangements of parts hereinafter described and claimed.

The invention will be best understood by 20 reference to the accompanying drawing forming a part of this specification, and in which,

Figure 1 is a plan view of a device embodying my invention, Fig. 2 is a side elevation of the same with portions broken away to expose underlying parts, and Fig. 3 is an enlarged section taken on line 3—3 in Fig. 2.

The preferred form of construction as 25 illustrated in the drawing comprises an arm pivoted to a table and adapted to swing only in a horizontal plane, and a lever is pivoted to the free end of said arm. The horizontal swinging arm is composed of members 3 and 4 joined together by the pivotal connection 30 5. The portion 3 is pivotally mounted on a pin 6 and said pin is carried by a casting 7 which is secured to a table 8 by means of bolts 9. The table 8 is provided with pieces 35 of sheet metal 10 to strengthen the portion 40 of the table to which the casting 7 is attached.

The free end of the portion 4 is provided 45 with a perforation in which is rotatively mounted a pin 11. Said pin 11 is provided with threads on which are mounted nuts 12 and lock nuts 13 adapted to lock the nuts 12 in desired positions. The pin 11 is adapted to be moved longitudinally in the perforation of member 4 in order to adjust it there- 50 in. Pivots secured to the lower end of pin 11 is a lever 14 pivoted as at 15. A sad iron 16 is provided with an arm 17 secured to its top side and said arm 17 is pivoted to lever 14 as at 18. At the rear end of the sad 55 iron 16 is secured a member 19 having two laterally projecting fingers 20 and 21. The

finger 20 is adapted to limit upward swinging of the rear portion of sad iron 16 and finger 21 is adapted to limit downward swinging of the rear end of said sad iron 16 as will be readily understood. A spring 60 catch 22 is secured to the lever 14 and adapted to engage the top of pin 11 to lock the lever 14 and sad iron 16 in inoperative positions, such as indicated in dotted lines in 65 Fig. 2.

In operation, the device is mounted on a table as indicated. The pivotally jointed and connected arm composed of members 3 and 4 permits said sad iron 16 to be moved 70 over all portions of the table 8. A garment or other material which it is desired to iron is placed in position on table 8 and the iron 16 placed thereon by means of lever 14 and operated in the usual manner by manipulating lever 14. The end of lever 14 provided with the handle 23 is preferably longer than the end of said lever between pivotal points 15 and 18 so that great pressure may be applied to the sad iron 16 by the operator. 75 The pin 11 is made adjustable in its perforation in member 4 to permit of adjusting said pin to effect greater or less pressure on iron 16 as desired. The fingers 20 and 21 are provided so that the operator may direct greater 80 pressure at the rear or front portion of the iron when desired. Said fingers also hold the iron in position when lifted from its full line to its dotted line position indicated in Fig. 2. The catch 22 serves as a lock for 85 locking the sad iron 16 in inoperative position when it is desired to change material to be ironed or for any other purpose. The arm composed of members 3 and 4 and their connection with the table 8 is made of sufficient 90 strength to prevent upward movement of pin 11 in order to permit the operator to apply great pressure to the iron 16 by pressing downwardly on the handle 23.

While I have illustrated and described the 100 preferred form of construction for carrying my invention into effect, this is capable of variation and modification without departing from the spirit of the invention. I, therefore, do not wish to be limited to the 105 precise details of construction set forth, but desire to avail myself of such variations and modifications as come within the scope of the appended claims.

Having described my invention what I 110 claim as new and desire to secure by Letters Patent is:

1. In a device of the kind described, an arm pivoted to swing in a horizontal plane; a lever pivoted to the free end of said arm; a sad iron pivotally connected with said lever; and means on said sad iron engaging said lever and adapted to limit the pivotal movement of said sad iron, substantially as described.
2. In a device of the kind described, an arm pivoted to swing in a horizontal plane; a lever pivoted to the free end of said arm and having a perforation therethrough; a sad iron pivotally connected with said lever;

a member carried by said sad iron and extended through said perforation; a stop on said member under said lever; and a stop on said member above said lever, substantially as described.

In testimony whereof I have signed my name to this specification in the presence of two subscribing witnesses.

NICHOLAS OROS.
